By Clarence O'Brien

Attorney

UNITED STATES PATENT OFFICE.

LARS JOHNSON AND WILLIAM WELLINGTON WELLS HILLSON, OF OSSINING, NEW YORK.

FLOOR JACK.

Application filed March 3, 1926. Serial No. 91,985.

This invention relates to an improved floor jack of the type used for assisting in laying flooring to insure a firm and close joint between the abutting edges of the floor board while nailing the latter in place.

My principal aim is to generally improve upon structures of this class by providing one including novel details and a new arrangement and association thereof providing an efficient structure which serves to effectively accomplish the purpose for which it is intended.

The particular details and new combination thereof will become apparent from the following description and drawing.

In the accompanying drawing forming a part of this application, and in which like numerals are employed to designate like parts throughout the same:

20 Figure 1 is a side view of a tool or jack constructed in accordance with the present invention showing the approximate manner in which the same is used.

Figure 2 is a section taken approximately 25 upon the plane of the line 2—2 of Figure 1 looking downwardly.

Figure 3 is a detail section taken on the line 3—3 of Figure 1.

Figure 4 is a perspective view of one of 30 the details.

In the drawing, the reference character 1 designates a horizontal stud. This however may represent sub-flooring. The floor boards are represented by the reference characters 2. It is obvious to persons familiar with tools of the kind described that it is the purpose thereof to hold the board being nailed firmly against the one already nailed in order that a tight dust proof joint 40 may be had.

In carrying out the present invention, I provide a base plate 3 which has a notch formed in its outer end as represented in Figure 2. Fastened to the intermediate 45 portion of the top of this base plate is a bracket 4 including spaced portions having bearings in which the pintles of a toothed rack bar 5 are journaled. This bar is bowed longitudinally and is pivotally connected as 50 at 6 with the lower portion of a manually rocked lever 7. The lower portion of this lever is provided on opposite sides with face plates 8, and is formed on its rear side with a pocket 9 in which the upper end of a 55 retaining pawl 10 is pivotally mounted. It

will be noted that the lower end of this pawl is twisted as shown plainly in Figure 3 to provide a part 11. This part is bifurcated and the furcations straddle the toothed portion of the rack bar. A tooth is formed 60 between these furcations and engages with the teeth of the rack bar, thus holding the lever in different adjusted positions. It will be noticed that a releasing latch 12 is pivoted between its ends to the intermediate 65 portion of the rack bar and the outer end thereof extends between one of the furcations of the part 11, and the rack bar shown in Figure 3. The outer end carries a right angular extension 13 which overlies the upper edge of the rack bar. In this way the downward swing of the latches is limited. It will be noted that the inner end of the latch is formed into a foot piece 14 adapted 70 to be engaged by the operator's foot. It is 75 evident that with this arrangement that by pressing down on the foot piece and lifting upwardly on the outer end of the latch, the same will serve to disengage the tooth of the dog 10 from the rack bar and to allow free 80 swinging movement of the lever.

In connection with this device I employ a special pressure providing member 15 having a downturned flange 16 to engage the edge of the floor board as shown in Figure 85 1. This member is provided with spaced hooks 17, and with outstanding ears 18 disposed at right angles to each other. This pressure member 15 fits in the cut out portion or notched outer end of the base plate 90 3 as shown in Figure 2 and the ears 18 overlie the extensions of the base plate in order to provide a fulcrum for the lever, it is provided at its bottom with outstanding lugs 95 19 having openings through which the hooks 17 extend.

It is yet to be pointed out that a suitable anchoring device is provided for the base plate, and this comprises a pair of arcuate metal strips 20 fastened to the intermediate 100 portion of the base plate as at 21 and fastened at their outer ends to a cross piece 22. In turn, a downwardly curved anchor 23 is fastened to the intermediate portion of the cross piece, and is provided at its free end 105 with spurs adapted to be driven into the stud 1.

In practice the operator places the base plate 3 upon the stationary floor board and allows the outer end portion thereof to over- 110

hang the board which is about to be nailed. Then the operating lever 7 is brought to the approximate position shown in Figure 1 and the downturned flange 17 of the pressure member 15 is brought against the longitudinal free edge of the floor board. The operator stands on the base plate on the right hand side of the operating lever in Figure 1 and pushes the lever away from him. In so doing the lower end of the lever moves inwardly and exerts a pull upon the hook 17, and in turn upon the member 15, thus drawing or pressing the loose floor board tightly up against the stationary one. As the lever is thus pushed, the pawl ratchets over the teeth of the rack bar and holds the lever in the position to which it has been moved. Sliding of the base plate is prevented by the anchoring means comprising the parts 20 to 23 inclusive. After the floor board has been nailed, the operator disengages the pawl by lifting the latch 12.

The operation of the device will be clear to those skilled in the art to which the invention relates by considering it in connection with the drawing. Also the details and relative arrangement will be plain and a more lengthy description is therefore thought unnecessary.

30 While the preferred embodiment of the invention has been shown and described, it is to be understood that minor changes coming within the field of invention claimed may be resorted to if desired.

35 Having thus described the invention, what we claim as new and desire to secure by Letters Patent is:—

1. In a floor jack of the class described, a base plate having a notch at one end, a 40 relatively slidable pressure member fitting into said notch and having a downturned flange adapted to engage a floor board, an operating lever, a detachable operating connection between the lower end of said lever and said pressure member, anchoring means carried by the intermediate portion of said base plate, and releasable retaining means interposed between the base plate and lever.

2. In a floor jack of the class described, a 50 base plate having one end provided with a

notch, a relatively slidable pressure member disposed in said notch and having a downturned flange engageable with the floor board and upstanding hooks at its opposite end, a vertically disposed operating lever having 55 means detachably connected with said hooks, a rack bar pivotally connected with the intermediate portion of the base plate and pivotally connected with the lower portion of said lever, a pawl carried by said lever and 60 cooperable with said rack bar, release means carried by said rack bar and associated with said pawl, and anchoring means connected with said base plate and extending over and outwardly beyond said member to be engaged with a relatively stationary part of the floor.

3. In a floor jack of the class described, a base plate provided at one end with a notch, a relatively slidable pressure producing member disposed in said notch and having a downturned flange engageable with the floor board and provided at its opposite inner end with upstanding hooks, a vertically disposed operating lever having means 65 detachably connected with said hooks, whereby it is swingably connected with said pressure member, a toothed rack bar pivotally connected with the intermediate portion of the base plate at one end and pivotally connected at its opposite end with the lever, a ball carried by the lever and cooperable with the teeth on the rack bar, a pivotally mounted release device carried by the rack bar and associated with said pawl for disengaging the latter from said teeth, said release device being provided with a foot piece, and anchoring means connected with the base plate comprising a pair of arcuate strips between which the pivoted end of the 70 lever is disposed, a cross piece connected to the outer end of said strip, and a resilient spur equipped element carried by said cross piece and adapted to be embedded in a relatively stationary part of the floor.

95 In testimony whereof we affix our signatures.

LARS JOHNSON.

WILLIAM WELLINGTON WELLS HILLSON.
